(57) **CLAIM**

The ornamental design for a luminaire with optical control, as shown and described.

DESCRIPTION

FIG. 1 is a bottom perspective view of a luminaire with optical control, showing our new design;

FIG. 2 is a top perspective view thereof;

FIG. 3 is a bottom view thereof;

FIG. 4 is a top view thereof;

FIG. 5 is a right side view thereof;

FIG. 6 is a left side view thereof;

FIG. 7 is a front view thereof; and,

FIG. 8 is a rear view thereof.

The broken lines shown in the figures illustrate portions of the luminaire with optical control that form no part of the claimed design. The dash-dot-dot lines passing through each embodiment indicate that the portions of the luminaire with optical control between the dash-dot-dot lines form no part of the claimed design.

1 Claim, 6 Drawing Sheets
